(57) **CLAIM**

The ornamental design for an eye tracking apparatus, as shown and described.

DESCRIPTION

FIG. 1 is a top plan view of an eye tracking apparatus;
 FIG. 2 is a bottom plan view of an eye tracking apparatus;
 FIG. 3 is a front view thereof;
 FIG. 4 is a right side view thereof;
 FIG. 5 is a left side view thereof;
 FIG. 6 is a top perspective view thereof; and,
 FIG. 7 is a bottom perspective view thereof.
